UNITED STATES PATENT OFFICE.

EUGENE CAMPBELL, OF SOUTH WESTERLO, NEW YORK.

IMPROVEMENT IN SNOW-SHOVELS.

Specification forming part of Letters Patent No. 173,209, dated February 8, 1876; application filed January 7, 1876.

To all whom it may concern:

Be it known that I, EUGENE CAMPBELL, of South Westerlo, in the county of Albany and State of New York, have invented a new and useful Improvement in Snow-Shovel, of which the following is a specification:

Figure 1 is a longitudinal section of my improved shovel, taken through the line $x x$, Fig. 2. Fig. 2 is a top view of the same.

Similar letters of reference indicate corresponding parts.

The object of this invention is to furnish an improved wooden snow-shovel, which shall be so constructed that it may be used for shoveling the snow from a tin, zinc, or cement roof without injuring the roof.

The invention consists in the combination of the runners with the blade of a shovel, as hereinafter fully described.

A represents the blade of a wooden snow-shovel, which is provided with a handle, B, in the usual way. The edge of the blade A may be faced with thin sheet metal C, to prevent wear. D are beads or ribs, which are attached

to the under side of the blade A, and the forward ends of which are curved upward to serve as runners, to slide over the roof when the shovel is being used.

The runners D prevent the edge of the blade A from catching upon the seams of a metal roof, or upon inequalities in a cement roof, and thus protects the roof from being injured. The runners D also cause the shovel to work easier as they slide over the surface, and prevent the blade from rubbing upon said surface.

I do not limit myself to wooden shovels, as the runners D can be applied to shovels of other material with equal advantage.

Having thus described my invention, I claim as new and desire to secure by Letters Patent—

The combination of the runners D with the blade A of a shovel, substantially as herein shown and described.

EUGENE CAMPBELL.
